Patented Sept. 9, 1919.

INVENTOR
Walter B. Wood
BY
E. M. Marshall
ATTORNEY

UNITED STATES PATENT OFFICE.

WALTER B. WOOD, OF DOWNTON, PENNSYLVANIA.

SEAL.

1,315,649.

Specification of Letters Patent.

Patented Sept. 9, 1919.

Application filed February 4, 1919. Serial No. 274,883.

To all whom it may concern:

Be it known that I, WALTER B. Wood, a citizen of the United States of America, and a resident of Downingtown, Chester county, 5 and State of Pennsylvania, have invented certain new and useful Improvements in Seals, of which the following is a specification, reference being had to the accompanying drawings, forming a part thereof.

10 My invention relates to that class of devices which are used for sealing the locks of car doors, but my particular device is also applicable to seal boxes, packages, or bundles.

15 The object of my invention is to provide a simple and inexpensive device which is easily applied and which cannot be removed without first breaking a part thereof, and this cannot be done without leaving traces which may be easily detected. Thus, it is 20 adapted to serve as a positive indication of tampering if the sealed door, package, or bundle has been opened without authority.

In order that my invention may be thoroughly understood I will now proceed to 25 describe the same in the following specification, and will then point out the novel features thereof in appended claims.

Referring to the drawings:

Figure 1 is a front elevation of a part of 30 a car door with a lock thereon of common form and with a seal which embodies my invention applied to the lock.

Fig. 2 is an elevation on a larger scale, of 35 the seal shown in Fig. 1, with some of the parts thereof shown in section.

Fig. 3 is a sectional elevation of the same seal with its parts shown in its relative positions which they assume before being locked together. This figure also shows a part of 40 the clamping or locking tool which is used in applying the seals.

Figs. 4 and 5 are perspective views showing respectively the back and front of a metallic locking member which forms a part 45 of this device.

Fig. 6 is a perspective view of a block which also forms a part of the device.

Fig. 7 is a sectional elevation of certain 50 parts of a seal of modified construction, which also embodies this invention.

Fig. 8 is an elevation of the locking pin of the form used with the construction illustrated in Fig. 7.

Like characters of reference designate 55 corresponding parts in all the figures.

10 designates a rectangular block of any suitable material such for example as wood.

This has a transverse groove 11 cut across its upper surface near the center and a hole 12 continuing from the bottom of this slot down to the bottom of the block. At the bottom 60 the hole is countersunk or flared as shown at 13. 14 is another hole from an end of the block intersecting the hole 12 intermediate its ends at right angles. 65

15 is a channel-like metallic locking member with the upper ends of its sides bent outwardly at right angles to form flanges 16. The back of the channel-shaped part of this piece terminates at 17 short of the 70 sides. Holes are punched through the sides of this member as shown at 18.

This locking member is driven into the hole 12 until the upper surfaces of the flanges are flush with the upper surface of 75 the block. Then the holes 18 in the sides of the locking member are in axial alignment with the hole 14 of the block. When in this position the upper edge 17 of the back of the channel will be about level with 80 the lower edge of the cut 11.

20 is a strip of flat flexible metal. One end of this strip is threaded through the hole 12 between the sides of the member 15 and bent under one of these sides as shown at 85 21. 22 is a locking pin preferably pointed at its inner end. This is inserted in the hole 14 with its pointed end up to but not protruding through the adjacent side of the locking member 15. 90

The locking tool comprises two jaws 30—31 which are pivoted together at 32. The upper end of the jaw 30 forms a rectangular pocket of such size and shape as to receive a corner of the block 10 and to 95 position this block in relation to the other jaw 31. On this other jaw is a plunger 34 which, when a block is inserted and positioned in the pocket 33 of the jaw 30, will be in axial alignment with the hole 14. 100

In Fig. 1 the car door lock shown comprises a hasp 40, a staple 41, and a sliding bolt 42 through which near its lower end, is a transverse slot 43.

Before describing specifically the construction of the device shown in Figs. 7 and 8, I will describe the manner in which this device is used. The end of the flat metallic strip 20 is passed through the part to be sealed, such for example, as through the slot 110 43 through the bolt 42, and is then passed down through the hole 12 until it projects through the block 10. The parts will then assume the relative positions in which they

are shown in Fig. 3. After this the clamping tool is applied and by moving the jaws 30 and 31 together, the plunger 34 will push the locking pin 22 through both parts of the 5 flexible metallic strip 20 and into the position in which it is shown in Fig. 2. After this, it is impossible to release the bolt 43 without first breaking some part of the seal. This is because the pin 22 is absolutely inac- 10 cessible. The slot 11 and the depressed upper end 17 of the back of the locking member, are arranged so that it is impossible for anyone to break by bending the parts of the strip 20 where they leave the locking mem- 15 ber 15, without showing clearly the broken ends.

In the form of the device which is shown in Fig. 7, the block 10 is of the same form and construction as that previously de- 20 scribed and the locking member 15^a is also the same, so that at least one of the holes 18^a therein is threaded. With this device the flexible metallic strip is applied to the device to be sealed in the same manner as that 25 which has been described, after which a pin 50, the end of which is threaded, is screwed into the threaded hole 18^a until the metal of the strip 21 is either punctured or is so de- 30 pressed that it cannot be removed from the block. No special tool is required for applying this form of seal but the pin 50 is made long enough to have its handle 51 project outside of the block and by means of 35 this handle the pin is screwed into the locking member 15^a. Between the handle and the threaded end of the locking pin, a trans- 40 verse cut 52 is made in the shank of the pin which reduces the strength of the device at that particular point so that after it has 45 been screwed into the device far enough for it to accomplish its locking function, a fur- 50 ther rotative pressure on the handle 51 will cause it to break at this point as shown in Fig. 7. It is obvious that after this shank 55 is once broken, it is impossible to unlock the seal.

I have illustrated and described several forms of my invention for the purpose of showing that I do not wish to limit myself 60 to any specific form of construction, and in fact I intend no limitations other than those imposed by the appended claims.

What I claim is:

1. A seal comprising a block, a locking 65 member of different material than that of the block therein having sides closely dis- 70 posed, at least one of which is provided with a perforation, a flat flexible strip extending from the locking member and having a free 75 end adapted to be inserted in the block near the perforated side of the locking member, across the perforation therein, said block be- 80 ing provided with a hole in alinement with 85 the perforation in the locking member, a 90 locking pin, and means for moving said pin 95 into the hole of the block into the flexible strip, with the pin lying wholly within the block.

2. A seal comprising a block, a metallic locking member therein having closely dis- 10 posed parallel sides, at least one of which is 15 provided with a perforation, a flat flexible strip extending from the locking member and having a free end adapted to be inserted 20 between the sides of the locking member and across the perforation therein, said block be- 25 ing provided with a hole in alinement with the perforation in the locking member, a 30 locking pin in said hole, and means for forc- 35 ing said pin through the perforation and into the flexible strip with the pin lying 40 wholly within the block.

3. A seal comprising a block, a metallic locking member therein having closely dis- 45 posed parallel sides provided with alining 50 perforations, a flat flexible strip between 55 said sides and extending from the locking 60 member and having a free end adapted to be 65 inserted between the sides of the locking 70 member and across the perforations therein, 75 said block being provided with a hole in 80 alinement with the perforations in the lock- 85 ing member, a locking pin in said hole, and 90 means for forcing said pin through the per- 95 forations and into both parts of the flexible 100 strip between the sides of the locking mem- 105 ber with the pin lying wholly within the 110 block.

4. A seal comprising a rectangular block 105 of wood provided with a transverse depres- 110 sion across the center of its upper side and with a hole extending downwardly through 115 the block, a channel-like metallic locking member in said hole with the back of its channel level with said depression, said member having closely disposed parallel 120 sides extending above the depression and bent outwardly to form flanges at the upper 125 surface of the block, said sides being pro- 130 vided with alining perforations within the 135 block, a flat flexible strip between said sides 140 with one end thereof bent under one of the 145 sides of said member, extending from the 150 member and having a free end adapted to be 155 inserted between the sides of the locking 160 member and across the perforations therein, 165 said block being provided with a hole in 170 alinement with the perforations in the lock- 175 ing member, a locking pin in said hole, and 180 means for forcing said pin through the per- 185 forations and into both parts of the flexible 190 strip with the pin lying wholly within the 195 block.

In witness whereof I have hereunto set my hand this 30th day of January, 1919.

WALTER B. WOOD.
